UNITED STATES PATENT OFFICE.

WILLIAM L. CALDWELL, OF INDIANAPOLIS, INDIANA.

ADVERTISING DEVICE.

SPECIFICATION forming part of Letters Patent No. 398,227, dated February 19, 1889.

Application filed November 20, 1888. Serial No. 291,390. (No model.)

To all whom it may concern:

Be it known that I, WILLIAM L. CALDWELL, a citizen of the United States, residing at Indianapolis, in the county of Marion and State 5 of Indiana, have invented certain new and useful Improvements in Advertising Devices, of which the following is a specification.

The object of my said invention is to provide a simple, convenient, and efficient device by which a very large number of advertisements can be displayed and brought prominently before the public in such a manner as to impress their contents forcibly upon the minds of those who see them, as will be hereinafter more fully described and claimed.

Referring to the accompanying drawings, which form a part hereof, and on which similar letters of reference indicate similar parts, Figure 1 is a side elevation of a device embodying my said invention, a portion being broken away to show the internal mechanism; Fig. 2, a horizontal section through the same on the dotted line 2 2; Fig. 3, a cross-section on the dotted line 3 3; Fig. 4, a detail sectional view on dotted line 4 4, and Fig. 5 a similar view on the dotted line 5 5.

In said drawings, the portion marked A represents the frame-work of the device, B the reels or rollers on which the display-curtains are mounted, and C said display-curtains.

The frame-work A is preferably in the form of a wagon-top or car, it being intended to mount the same on wheels and make the display on the public streets. Its sides are provided with three open spaces to receive the advertising-sheets, preferably representing panels, the middle one of which is the widest and intended for the principal display sheet 35 or curtain. The two sides of said frame are of a substantially duplicate construction, as shown, and the signs and advertising matter are thus displayed from each side of the car as it moves along. In the front space of each 40 side is mounted a bulletin-board, A', which is pivoted at the center of its top and bottom to arms a, which are hinged to the sides of the frame, as indicated by dotted lines in Fig. 1. Thus any current news can be displayed and the board reversed when desired, as when both sides are full of news of inter-

est, which it is desired to display from time to time. The interior of the frame-work is suitably arranged to support the reels and operating mechanism, and needs no special 55 description, except incidentally in describing said mechanism.

The reels or rollers B are shown as formed of heads arranged at each end and connected by a suitable number of ribs. The heads are 60 provided with journals which are mounted in suitable bearings on the internal frame of the device. Said reels extend from the rear end of the frame to the front of the central openings in its sides, and are arranged, one at the 65 top and one at the bottom, on each side of the structure, being located a short distance within said sides to allow curtains of any length to be reeled thereon.

The journals of the two lower rolls are extended through their front bearings and provided with pinions b on their outer ends, which mesh with the gear-wheels b' on the short shafts B', which are journaled in suitable bearings in the frame-work and provided with 70 bevel gear-wheels b² on their outer ends. Said bevel gear-wheels mesh with the gear-wheels b³ on the transverse shafts B², which are provided on their outer ends with the ratchet-wheels b⁴. Surrounding said ratchet-wheels, and loosely mounted on each of these 75 shafts, is a hollow lever, B³, having a cam-pawl, b⁵, arranged to be forced into engagement with the ratchet-wheel, a spring being provided to throw it back when the force is 80 removed. (See Fig. 5.) The rear ends of each reel are provided with a sprocket-wheel, b⁶, and each top reel is geared to the lower reel upon the opposite sides of the device by a sprocket-chain, B⁴, as shown in Fig. 3, and 85 90 for the purposes which will be presently described. The short shafts B' are also provided with ratchet-wheels B⁵, and a transverse lever, B⁶, provided with a pawl, b⁷, on its top, is pivoted to a hanger secured to the frame and 95 extends under each of said wheels B⁵, so arranged that the pawl will engage therewith and secure it from rotating in one direction, being held into engagement by a spring, b⁸, until said levers have been forced down, which 100 is done through a longitudinal lever, B⁷, pivoted centrally in a post extending up from

the floor, the inner end of which extends under the end of the lever B^6 , and the outer end of which extends to a position convenient of reach.

5 The main display-curtains or advertising-sheets C are each mounted on the top and bottom reel of one side. They are of a sufficient width to fit closely between the sides of the frame which surround the central opening and of a suitable length to accommodate the desired number of advertisements. They are attached at each end to the reel and pass over an idler, c , arranged at each corner of the frame in position to hold the curtains close against said frame. A rigid back, c' , is preferably mounted behind said curtains to prevent them from flapping or vibrating during the motion of the car.

The curtains C' are designed to fill the openings at the rear end of the structure, and are mounted upon the reels in the same manner as the curtains C , being designed to contain pictures of a comic or noticeable character to attract the attention of the public to 25 the advertisement appearing on the curtain C . As will be readily understood, these pictures may be of a purely comic design, or one which shall be appropriate for the corresponding advertisement upon the curtain C .

30 The operation of my said invention is as follows: The advertisements which it is desired to display are arranged upon the curtain C in such position that each will fill the space in the center of the frame-work, and a corresponding picture is provided upon the curtain C' , designed to fill the space in the frame alongside said advertisement. These curtains, being wound upon the reels, as before described, and it being desired to change the 35 advertisement displayed to view or bring another into view, one of the levers B^3 is raised the required distance, the pawl b^5 therein operated to engage with the ratchet-wheel b^4 , and is then forced down, and thus, through 40 the intermediate gearing, operates to rotate the reels just a sufficient distance to wind up the curtain upon one reel and unwind it from the other sufficiently to bring a new advertisement into view. By reason of the cross- 45 sprocket-chains upon the rear end of the rollers which gear them together, it will be seen that the operation of the gearing of one side also operates that of the other side of the device. Thus while one curtain is being wound from the top reel and wound onto the 50 bottom one the curtain upon the opposite side is being wound in the opposite direction. When, for any reason, it is desired to reverse the operation or direction of winding, as when 55 one curtain has been unwound its entire length, the lever upon the opposite side of the device is operated, which reverses the direction of the winding and again displays the advertisements successively, as will be readily understood. While the gearing of one side 60 is being operated the gearing on the other

side runs free from the lever B^3 , but is prevented from being operated too great a distance by the catch b^7 on the lever B^6 engaging with the ratchet-wheel B^5 on each side and holding it from turning except when force is applied, thus securing the desired tension to the curtains at all times, as will be readily understood. During the display any current news of especial interest can be readily posted 70 upon the bulletin-boards provided in the front portions of the sides of the car, and thus another attractive feature is added to the device, and one which will assist in fixing the advertisement in the minds of those who 75 see it.

Having thus fully described my said invention, what I claim as new, and desire to secure by Letters Patent, is—

1. In an advertising device, the combination of the frame-work, four reels or rollers arranged two at the top and two at the bottom of said frame-work, each top roller being geared to the opposite bottom roller, suitable mechanism for operating the same, and display-curtains mounted on said reels or rollers, substantially as set forth. 85

2. The combination, in an advertising device, of the frame-work, the bulletin-boards A' , mounted thereon, the four reels arranged 90 therein, two at the top and two at the bottom of said frame-work, the gearing for operating said reels, and separate display-curtains attached to the reels on each side of the device, substantially as set forth. 95

3. The combination, in an advertising device, of the frame-work A , the reels B , arranged two at the top and two at the bottom of said frame-work, and geared together, each top to the opposite bottom reel, the display-curtain C , mounted thereon and bearing a series of advertisements, the display-curtain C' , also mounted thereon and bearing a series of pictures calculated to attract attention to the advertisements on the curtain C , and the 100 operating mechanism, substantially as set forth. 105

4. In an advertising device, the combination of the frame A , the reels B , arranged therein substantially as described, the curtains C and C' , mounted upon said reels and passing over the idler-rolls c , mounted close to the sides of said frame-work, and the gearing for operating said reels, consisting of the levers B^3 , having the cam-pawls arranged to engage with the ratchet-wheels b^4 , the pinion upon the end of the journal to said reels, the intermediate gearing and the ratchet-wheel B^5 , and pawl engaging therewith, substantially as shown and described. 115 110 115

5. The combination, in an advertising device, of the frame-work provided with open sides, as described, the bulletin-boards arranged in the front openings, the four reels B , journaled inside said frame-work, and 120 geared together, the top roll on each side to the bottom roll on the opposite side, the cur- 125

tains C and C', carrying a series of advertisements and pictures mounted on reels and arranged to fill the middle and rear open spaces on the sides of said frame-work, and passing over the idler-rolls, and the back C', mounted behind said curtains to steady them in position, substantially as set forth.

In witness whereof I have hereunto set my hand and seal, at Indianapolis, Indiana, this 13th day of November, A. D. 1888.
